UNITED STATES PATENT OFFICE.

JOHN M. CRUM, OF JOHNSTOWN, PENNSYLVANIA.

ELECTRIC POWER JACK.

1,423,834.

Specification of Letters Patent. Patented July 25, 1922.

Application filed October 20, 1921. Serial No. 509,094.

To all whom it may concern:

Be it known that JOHN M. CRUM, a citizen of the United States, residing at Johnstown, in the county of Cambria and State of Pennsylvania, has invented certain new and useful Improvements in Electric Power Jacks, of which the following is a specification.

This invention relates to improvements in lifting jacks, and more especially to electrically operated power jacks.

An object of the invention is to provide a suitable electrically operated power jack which will be highly efficient in use and inexpensive to manufacture.

Another object of the invention is to provide an electric power jack which will be so constructed as to prevent any injury to the operating mechanism or motor, should the load slip or any part of the jack fail to function properly.

A further object of the invention is to provide a suitable jack which will be operated by an electric motor or generator of any size and using any kind of current, either high or low voltage.

Al still further object of the invention is to provide a suitable electric power jack, which will be provided with means for operating the motor in either direction to raise or lower the jack screw and means to stop the motor at will, and also a safety catch to prevent the jack screw from slipping when it is in the position desired.

Other objects will appear as the description proceeds.

In the accompanying drawings which constitute a part of my application,

Figure 1 is a side elevation of my improved electric power jack;

Figure 2 is a vertical sectional view through the said jack;

Figure 3 is a rear view of the jack, showing the safety handles, and lock for the jack screw;

Figure 4 is a plan view of my improved electric power jack, and

Figure 5 is a detail view of the safety lock or catch for preventing the slipping of the jack screw.

Like characters of reference are used throughout the following specification to designate corresponding parts.

The body 1 of the jack is provided with the spaced vertically extending flanges or wing portions 2, which are formed integral

with the body or jack housing 1. The lower portions of the flanges 2 extend out a considerable distance beyond the upper portions, as at 3, to provide additional space 60 for the housing of the motor or generator 4. This motor or generator 4, may be made in any desired size and horse power, and used with any kind of electric current, either alternating or direct, or battery current, and 65 of different voltages.

A gear cover or housing plate 5 is adapted to seat on the ends of the wing portions 2, to completely house the mechanism therein and protect the same from dirt or injury. 70

The motor 4 is of the reversible type, and is provided with switch buttons 6, 7 and 8 for operating the motor in one direction, stopping and reversing the motor, respectively. It will be understood that these 75 switch buttons may be replaced by any suitable or desired type of switches, as will be found most convenient and practicable in manufacturing the same. The switches extend up through the housing plate 5, as do 80 also the electric feed wires 9, which in use will be connected to the source of current supply.

Within the body 1 of the jack, is the central well 10 for the reception of the screw 85 threaded jack screw 11, which is adapted to operate therein. On the outer end of the jack screw 11 is the cap member or work rest 12, which is made preferably round, but may be made in any desired shape or form 90 to more readily hold the load to be lifted. The upper surface of the cap member 12 may be grooved as at 13 to prevent the load from slipping, or may be roughened in any manner desired. 95

An annular groove 14 is formed in the upper surface of the body 1, in which is placed the ball bearings 15. An internally screw threaded nut or operating gear follower 16 is threaded upon the jack screw 11, 100 and is provided with an annular groove 17, similar to the groove 14, to complete the race or housing for the ball bearings 15. It will be understood that the nut 16 rests upon the ball bearings 15, and rotates thereon. 105 Oil passages 18 are formed in the nut 16 to permit of the lubricating of the ball bearings 15. The periphery of the cap nut 16 is provided with the beveled teeth 19, thereby forming a beveled gear as well as an operating nut. Diametrically opposite each other are the vertically extending channels or slots 110

41. The lower end of the jack screw 11 is cut away to receive the ring 42 which extends flush with the surface of the screw. A removable pin 43 passes through the ring 42 and screw 11, and extends out beyond the opposite sides of the ring into the slots 41, to prevent the screw from rotating. A screw plug 44 is removably secured in the bottom of the well 10, to permit cleaning, 10 etc.

Cast one above the other and intermediate of the wing portions 2 on the flat side 20 of the body 1, are the bearing posts or studs 21 and 22. These studs are formed integral 15 with the body 1, and serve as an axle or support for the large gear wheel 23 and the smaller gear wheel 24, which intermesh one with the other. The gear wheel 23 is provided with a bevel gear surface 25 and also 20 the spur gear surface 26. The bevel gear 25 meshes with the bevel gear 19 on the nut 16, and the spur gearing 26 meshes with the spur gearing 27 on the small gear wheel 24. A considerably smaller spur gear 28 is carried 25 by the motor shaft 29, and intermeshes with the spur gearing 27 on the wheel 24. Thus it will be seen that when the motor is started, the jack screw will be raised or lowered according to the direction the motor 30 is running. All of the gearing and operating nut will be mounted on ball bearings, and therefore will have little to no friction to hinder the operation of the jack screw.

Since most of the gearing and motor are 35 encased within the wing portions 2 and housing plate 5, there will be no chance of any dirt getting into the operating mechanism, or the mechanism becoming injured from any object striking the jack.

40 Cast integral with the body 1 of the jack, and at only one side thereof, are the pair of ears or bearing wings 30, which has the vertical bearing rod 31 mounted there-between. Pivoted on the rod 31 is the safety locking 45 lever 32, which has formed thereon a section of an internal spur gear 33, which is adapted to be swung into engagement with the spur gear surface 26 of the gear 23, to lock the jack from slipping, when the desired adjustment is had. The adjacent wing portion 2 is provided with a small opening or passage 34, through which the gear section 33 may pass when being placed in engagement with spur gear surface 26.

55 A flange or annular extension 35 is cast integral with the bottom portion of the body 1, to give an additional supporting surface to the jack.

Cast integral with the upper portion of 60 the body 1 of the jack and at opposite sides thereof, are the spaced vertically extending ears 36, which are connected together by means of the bolts 37. Mounted on these bolts 37, are the handles 38, which are provided with the spaced arms 39, the same

being formed integral with the handles, to prevent the handles from lifting or swinging up further than a horizontal position, which would be possible if these arms did not contact or engage with the wall of the 7 body 1. Thus it will be seen that it will be impossible for the person or persons carrying the jack to pinch or injure their fingers.

7 Detachably mounted on the bolts 37 is a bale handle 40, which will permit of the carrying of the jack on a pole, should the weight of the jack be too great for two persons to carry by the handles. This bale handle may be detached at will, or may be done away with in the smaller sizes of jacks.

8 It will be understood that I do not limit myself to the specific form of construction, as many minor changes in detail of construction may be resorted to without departure from the spirit of the invention.

9 It will further be understood that as many cogs as necessary may be used on different sizes of jacks to reduce to the proper speed. The gear cover or housing plate 5 may also be made in two parts if desired and held in position with stud bolts or in any desired manner, so that more ready access may be had to repair the gearing or motor if necessary.

Having thus described my invention what I claim as new and desire to secure by Letters Patent of the United States is:

1. An electric power jack comprising a body portion, spaced laterally extending wing portions formed integral therewith, a jack screw operable in said body, a nut or follower carried by said screw means for preventing said screw from rotating, an electric motor positioned between said spaced wing portions, and means connecting said motor with said nut for operating the jack.

2. An electric power jack comprising a body portion, spaced laterally extending wings formed integral therewith, a jack screw operable in said body, a nut or follower carried by said screw and rotatably mounted on said body means for preventing said screw from rotating, a motor positioned between said laterally extending wings, a train of gearing connecting said motor with said nut, and means for operating the motor in forward or reverse direction, or stopping the same.

3. An electric power jack comprising a body portion, spaced laterally extending wings formed integral therewith, a jack screw operable in said body, a nut or follower carried by said screw means for preventing said screw from rotating, an electric motor or generator positioned between said laterally extending wings, a train of gearing connecting said motor and nut, and a gear cover or housing plate detachably secured to said wing portions for housing the operating mechanism.

4. An electric power jack comprising a body portion, spaced laterally extending wings formed integral therewith, a jack screw operable in said body, a nut or fol-
5 lower carried by said screw means for preventing said screw from rotating, said nut having its periphery formed into a bevel gear, a combined bevel and spur gear mounted at the side of said jack body and inter-
10 meshing with the bevel gearing on the said nut, a smaller gear mounted below said combined bevel and spur gear and meshing therewith, a motor mounted between said wing portions, and a spur gear carried by
15 said motor and intermeshing with said last mentioned gear, whereby the jack screw may be raised or lowered as desired.
5. An electric power jack comprising a body portion, spaced laterally extending wings formed integral therewith, a reversible motor positioned between said wings, a jack screw operable in said body, a nut carried by said screw, said nut being positioned adjacent the top of said body and mounted
20
- upon ball bearings said body being provided with oppositely disposed vertically extending channels, detachable means carried by said screw adapted to slide in said channels to prevent said screw from rotating, a plurality of stub axles or shafts formed integral with said body, intermeshing gears mounted thereon, one of said gears meshing with said nut and the other meshing with a relatively smaller gear mounted upon the motor shaft, a cover plate detachably connected to said wings, and motor control switches, passing through said cover, for operating the motor in the desired direction or for stopping the same.
6. An electric power jack comprising a body portion, a jack screw operable therein, an electric motor encased within said body, means connected with said motor for operating said screw means for preventing said screw from rotating, and means locking the screw from accidental movement.

In testimony whereof I affix my signature.
JOHN M. CRUM.
